C. A. PARSONS AND S. S. COOK.
STEAM SUPERHEATER.
APPLICATION FILED APR. 27, 1917.

1,438,397.

Patented Dec. 12, 1922.

Inventors:

Charles A. Parsons, and
Stanley S. Cook,

by Spear, Philadelphia, Davidson & Spear
Atty's.

UNITED STATES PATENT OFFICE.

CHARLES ALGERNON PARSONS AND STANLEY SMITH COOK, OF WALLSEND-ON-TYNE,
ENGLAND; SAID COOK ASSIGNOR TO SAID PARSONS.

STEAM SUPERHEATER.

Application filed April 27, 1917. Serial No. 165,048.

(GRANTED UNDER THE PROVISIONS OF THE ACT OF MARCH 3, 1921, 41 STAT. L., 1313.)

To all whom it may concern:

Be it known that we, CHARLES ALGERNON PARSONS and STANLEY SMITH COOK, both subjects of the King of Great Britain and 5 Ireland, residing at Turbinia Works, Wallsend-on-Tyne, Northumberland, England, have invented certain new and useful Improvements in and Relating to Steam Superheaters (for which we have filed application 10 in England May 13, 1916, Patent No. 108,690), of which the following is a specification.

The present invention consists in preventing excessive heating of a superheater when 15 the ordinary consumption of steam is reduced or ceases, by the provision of an additional relief valve at the steam exit of the superheater arranged to blow off at a lower pressure than the relief valve on the boiler so 20 that at all times when the steam consumption is reduced a flow of steam is caused through the superheater which is thus prevented from attaining an excessive temperature.

In the drawings:

25 Fig. 1 is a view of an ordinary Scotch boiler provided with a superheater.

Fig. 2 is a detail view of the safety valve of the superheater.

In carrying the invention into effect as 30 illustrated, the boiler *a* is of the ordinary Scotch type and the superheater *b* is fitted in the uptake *c* of the boiler. The steam leaves the boiler *a* and passes through the valve *l* to the superheater whence it passes 35 through the safety valve *e* to the stop valve *m*. The safety valve *e* is provided in addition to the ordinary boiler safety valve *g* and the safety valve *e* is set to blow off at a lower pressure than the safety valve *g*. By re- 40 taining the ordinary boiler safety valve *g* valves *l m n* can be fitted by means of which the superheater can be shut off and the steam passed direct from the boilers to the main

engines if desired. Any known baffling devices may be provided adapted to be brought 45 into position to protect the superheater tubes when these are not in action.

Fig. 2 shows the superheater safety valve. The spring *o* is set to correspond to a blow off pressure lower than the pressure to which 50 the boiler safety valve is set. The pipe *s* is connected to a high pressure steam space in the main engines so that the steam pressure in the chamber *t* acting on the annular area *v* increases the total downward force 55 on the valve. This additional force on the valve will enable the maximum pressure to be carried at high powers, while at low powers the valve will blow off at lower pressures. Additional security is thereby given 60 to the superheater, as, under any running conditions, any reduction in the power increases the liability of the superheater safety valve to blow off.

Having now fully described and ascertained our said invention and the manner in which it is to be performed, we declare that 65 what we claim is:—

In combination, in a steam boiler system, a superheater for superheating the steam on 70 its way to the engines and a relief valve at said superheater discharging to atmosphere and opening automatically to induce a circulation of saturated steam through the superheater when the pressure therein rises 75 to a prescribed limit, said valve being subjected to a closing pressure from steam in the high pressure steam space of the engines to place a resistance on the valve variable according to the pressure of the steam 80 at high and low powers of the engine, substantially as described.

In testimony whereof, we have affixed our signatures.

CHARLES ALGERNON PARSONS.
STANLEY SMITH COOK.
